Application February 20, 1951, Serial No. 211,854

4 Claims. (Cl. 69—39.25)

1

This invention relates to driving mechanism, and particularly to mechanism driven by a turbine wheel deriving its energy from pressure fluid directed against the peripheral vanes, or buckets, of the turbine wheel.

An object of the invention is to provide means for deflecting variable amounts of pressure fluid away from the turbine buckets, and thereby controlling the speed of rotation of the turbine.

Another object is to provide a pressure fluid generator of novel construction, one feature of which is the mounting of a fluid discharge nozzle in the end face of a cylinder containing a combustible material in solid propellant form; the said end face being disposed in a plane parallel to the face of the turbine wheel, and closely adjacent thereto.

Another object is to provide swivel mounting means for a pressure fluid generator of the character indicated, which mounting means facilitates rotation of the generator about its longitudinal axis, to shift the discharge nozzle out of exact alignment with the periphery of the turbine wheel, whenever the latter tends to deviate from a speed characteristic corresponding to the required electric current frequency output of an alternating current generator mechanically driven from said turbine wheel.

Another object is to provide mutually opposing means for controlling the degree of rotation of said pressure fluid generator about its longitudinal axis.

These and other objects and features of the invention will be apparent upon reference to the following description of the embodiment of the invention illustrated in the accompanying drawings wherein:

Fig. 1 is a longitudinal sectional view of a pressure fluid generator and a housing in which the generator is adapted to rotate, to a limited degree; the view also including a showing of a portion of a turbine wheel mounted in said housing for rotation about an axis parallel to the axis of said pressure fluid generator;

Fig. 2 is another longitudinal sectional view, showing the complete turbine wheel and the gear assemblies rotated by the wheel, which gear assemblies drive the alternating current generator above referred to, and also a centrifugal governor controlling the limited rotation of the pressure fluid generator;

Fig. 3 is a detail view of the torsion spring which exerts a rotative effort upon the pressure fluid generator in opposition to the centrifugal governor;

Fig. 4 is an end view of the pressure fluid generator;

Fig. 5 is a sectional view of the nozzle end of the pressure fluid generator; and

Fig. 6 is a diagram of the gear assemblies, showing their disposition in relation to the position occupied by the pressure fluid generator.

In these drawings the pressure fluid generator is shown as a cylinder 10 mounted on a ball-bearing assembly 11, intermediate the ends of

10 housing 12, and on a sleeve bearing 13 located at one end of housing 12. The housing 12 extends below the cylinder 10, and includes two cylindrical compartments 14 and 15 carrying

15 ball-bearing assemblies rotatably supporting a pair of shafts 16 and 17, respectively, the former being integral with the turbine wheel 18, and the shaft 17 being flanged at one end to receive

20 a pinion 19 and a large gear 20. Pinion 19 meshes with, and drives, a second pinion 21 aligned with a boss 22 of the housing; the said

boss 22 being adapted to receive the housing of a hydraulic pump or other accessory, depending upon the nature of the installation. Gear

25 20 receives its rotation from pinion 23, with which it is in mesh, and pinion 23 is in turn rotated by the turbine wheel 18, by reason of the threaded connection of pinion shank 24 to turbine shaft 16. A second pinion 26 is keyed to the shank 24 and drives a gear 27 (see Fig. 6) aligned with an alternating current generator mounted on rectangular plate 28.

A centrifugal governor 31 is aligned with a gear 32 (Fig. 6) and driven by said gear, which gear is in turn driven by pinion 19. The governor 31 includes a lever 33 pivoted on a shaft

35 34 (Fig. 1), which lever rocks about the axis of said shaft 34 as the speed of the drive deviates from the speed which is correct for proper frequency in the current being generated in the unit driven by gear 27. Rocking of lever 33 produces a swiveling of the cylinder 10 by reason of the resultant pressure of lever finger 36 upon the pin 37 which projects radially outward from the wall of cylinder 10; such swiveling being opposed, however, by the torsion

40 spring 38 whose one end 39 is secured within a recess 40 in a flange 41 of the cylinder, and whose opposite end 42 is hooked about a pin

45 43 anchored in the wall of housing 12.

The end wall 51 of the cylinder 10 is bored obliquely to form a cylindrical compartment to receive a venturi-shaped nozzle 52 whose discharge end is aligned perfectly with the pitch circle of the buckets 53 of the turbine wheel,

55 when the latter is rotating at the desired speed.

When, however, there is a speed deviation, the combined effect of the mutually opposing governor lever 33 and torsion spring 38 is to rock the cylinder 10, and hence the nozzle 52, away from said position of perfect alignment, thus diverting more or less of the generated pressure fluid away from the buckets 53, according to the magnitude of the deviation. The resultant decrease of effective energy application promptly restores the turbine wheel to the desired speed, whereupon the cylinder 10 reverts to its normal angle, by the restoring effect of spring 38. The housing 12 is provided a suitable fluid exhaust opening, not shown, adjacent the turbine compartment. The solid combustible 61 may be ignited by an electric firing element 62, to initiate the fluid pressure generating cycle. The time required for complete combustion may vary between 20 seconds and two minutes, depending upon the type of combustible pellet employed.

The invention is particularly useful as a "power pack" for guided missiles, or rockets, the gyro-controls of which require electric current of fairly constant frequency, and the hydraulic controls of which likewise require hydraulic fluid delivery of fairly constant pressure, for the duration of their relatively brief operating span.

The invention, however, is not limited to this particular use, nor is it limited to the illustrated contours and relationships of its component parts. Other embodiments, insofar as they utilize the principles herein disclosed, are embraced herein.

In the appended claims the term "buckets" is intended to include vanes, blades, and other equivalent elements responsive to fluid pressure to produce rotation of the turbine.

What I claim is:

1. In a driving mechanism, a turbine wheel having a series of buckets disposed in a circle whose center is on the axis of rotation of said wheel, a housing surrounding said wheel, a fluid pressure generator in the form of a cylinder whose axis is parallel to said wheel axis, said cylinder terminating in an end wall disposed adjacent to said wheel, and parallel thereto, a fluid discharge nozzle mounted in said end wall, with its discharge end normally in alignment with said bucket circle, and speed-responsive means for turning said cylinder about its axis, and thereby shifting said discharge nozzle away from said position of alignment.
2. A driving mechanism as defined in claim 1, including a torsion spring surrounding said cylinder and tending constantly to return said cylinder to its normal position in relation to said bucket circle.
3. A driving mechanism as defined in claim 1, wherein said cylinder includes a pin projecting radially therefrom, and said speed-responsive means includes a lever engageable with said pin to exert turning pressure on said cylinder by way of said pin.
4. A driving mechanism as defined in claim 1, wherein said cylinder contains a charge of combustible material adapted to burn slowly and thereby generate a volume of fluid at relatively high pressure, and means extending through one end wall of said cylinder to initiate the burning cycle.

ROMEON M. NARDONE.
